IMPROVEMENT IN BUCKLES.

THOMAS B. DE FOREST, OF BIRMINGHAM, CONNECTICUT.

Letters Patent No. 59,896, dated November 20, 1866

SPECIFICATION.

TO ALL WHOM IT MAY CONCERN:

Be it known that I, THOMAS B. DE FOREST, of Birmingham, in the county of New Haven, and State of Connecticut, have invented a new Improvement in Buckles; and I do hereby declare the following, when taken in connection with the accompanying drawings and the letters of reference marked thereon, to be a full, clear, and exact description of the same, and which said drawings constitute part of this specification, and represented in—

Figure 1 a front view of the buckle complete.

Figure 2, the frame.

Figure 3, the tongue.

Figures 4 and 5, the construction of the sleeve which unites the tongue and frame.

Figure 6, a section in line $z-z$, of fig. 1. And in

Figures 7 and 8, the manner of securing the buckle to a strap.

This invention relates more particularly to the construction of buckles such as are used for wearing apparel, but is equally applicable to other purposes, and consists in the peculiar manner of forming and jointing the tongue to the frame, as also in the manner of securing the buckle to the strap.

To enable others to construct and use my improvement, I will proceed to describe the same as illustrated in the accompanying drawings.

A is the frame, B B, the tongues. The frame I form from a piece of round or other wire, as seen in fig. 2, flattening the side a , or not, as may be preferred, and of proper length so as to leave a space, C, between the two ends; and I form the two tongues from similar wire by bending into the form seen in fig. 3, each of the tongues pointed in the usual manner, the width of the two tongues corresponding to the space C in the frame. The sleeve which is to unite the tongues with the frame I form from a piece of thin sheet metal, as seen in fig. 5, of the length of one side of the buckle, perforated at $d d$, corresponding to the two tongues, B B; I then double the blank D into the form, as seen in fig. 4, then place the two tongues through the two perforations, $d d$, and the open side of the buckle into the sleeve, as seen in fig. 4, then close the sleeve around the bar of the tongue and the two ends of the frame, as seen in figs. 1 and 6, and the buckle is complete. Thus I have formed in an extremely simple manner a very strong and durable buckle without any of the objections which exist in buckles of similar appearance, and very much cheaper than the buckles in general use; as the labor required in their manufacture is no more, and the quantity of metal used much less. The buckle thus complete may be applied in the usual manner, but this construction affords a much better security, and which security forms an important part of this invention, and which I illustrate in figs. 7 and 8. The three parts of the buckle are furnished to consumers in the form seen in figs. 2, 3, and 4, who unite them with the strap in the following manner: The two tongues are first inserted through the strap near its end, then in the manner before described through the two perforations in the sleeve, and the frame also inserted, as before described, and the sleeve then closed down over the strap as denoted more clearly in fig. 8; this finishes and secures the buckle to the strap by the same operation, in an extremely neat and workmanlike manner, and by security which cannot be detached by ordinary or reasonable usage.

This manner of attaching the buckle to the strap by means of the sleeve around the tongue bar, may be employed in other buckles.

Having thus fully described my invention, what I claim as new and useful, and desire to secure by Letters Patent, is—

1. The combination of the frame A, the tongues B B, and the sleeve D, when the said sleeve D serves to hinge the tongues to the frame, substantially in the manner as herein set forth.

2. I claim securing the said buckle to its strap by means of the sleeve D around the bar and over the strap, substantially as herein set forth.

THOMAS B. DE FOREST.
